Application November 30, 1934, Serial No. 755,328

11 Claims. (Cl. 175—365)

Our invention relates generally to electrical apparatus, and more particularly to electrical systems for converting unidirectional current into alternating or pulsating current.

5 An object of our invention is the provision of an electrical system to energize an electrical load having a variable resistance.

Another object of our invention is to provide for energizing an electrical load having a variable 10 resistance from a direct current source by utilizing the combination of a high leakage reactance transformer and an interrupter for causing current to flow intermittently in the primary winding of the transformer.

15 A further object of our invention is the provision of a high leakage reactance transformer and an interrupter for causing current to flow intermittently into the primary winding of the transformer to energize an electrical load having a variable resistance, wherein the interrupter and the high leakage reactance transformer 20 mutually cooperate in such manner that the interrupter is protected from being over loaded by the action of the transformer limiting the value of the intermittent current flowing to the 25 primary winding, when the resistance of the electrical load decreased.

A still further object of our invention is to provide for decreasing the energization of the 30 coil which controls the interrupter, after the interrupter is set in operation.

Another object of our invention is the provision of a high leakage reactance transformer having two secondary windings for energizing an 35 electrical load having a variable resistance and an interrupter for causing current to flow intermittently in the primary winding, wherein the action of the high leakage reactance transformer is such that, when the resistance of the electrical 40 load decreases, the value of the intermittent current flowing to the primary winding is limited to protect the interrupter from being overloaded.

A still further object of our invention is the provision of a balanced, high leakage reactance 45 transformer having three magnetic shunts and two secondary windings, in which an electrical load having a variable resistance is connected across each of the secondary windings, and an interrupter for causing current to flow intermittently in the primary winding, wherein the action of the high leakage reactance transformer is such that, in the event one or both of the 50 secondary windings is shorted, or when the resistance of one or both of the electrical loads decreases, the value of the intermittent current

flowing to the primary winding is limited to protect the interrupter from being over loaded.

A further object of our invention is the provision of an auto transformer and an interrupter, wherein the interrupter is protected from being overloaded by the action of the auto transformer limiting the value of the intermittent current flowing to energize the auto transformer. 5

A further object of our invention is to provide for preventing arcing of the contacts of the interrupter. 10

Other objects and a fuller understanding of our invention may be had by referring to the following description, taken in conjunction with the accompanying drawing, in which like reference characters designate like parts, and in which; 15

Figure 1 is a diagrammatic view of an electrical system embodying the features of our invention.

Figure 2 is a diagrammatic view of a modified 20 form of our invention, in which an auto transformer is utilized.

Figure 3 is a diagrammatic view of another modified form of our invention, wherein a double secondary winding high leakage reactance transformer is employed, and 25

Figure 4 is a diagrammatic view of another form of our invention in which a balanced high leakage reactance transformer is employed.

With reference to Figure 1 of the drawing, our 30 invention comprises in general, a high leakage reactance transformer 9 having a split primary winding with two winding portions 13 and 14, and a split secondary winding with two winding portions 16 and 17, an interrupter 10 having 35 a vibrating contact 27 and two stationary contacts 28 and 29, and an actuating coil 25.

As diagrammatically illustrated, the transformer 9 includes a magnetic core 11, and a magnetic shunt 21 disposed between the primary 40 winding, and the secondary winding. The magnetic shunt 21 is so proportioned and designed that it offers a higher reluctance to the passage of the flux than the magnetic core 11. The increased reluctance of the magnetic shunt 21 may 45 be accomplished either by varying the cross sectional area thereof, or by utilizing air gaps between the ends of the magnetic shunt and the inside walls of the magnetic core 11. The secondary winding, which may be constructed of the 50 two parts 16 and 17 has the adjacent ends of the two windings 16 and 17 joined together, and connected to a ground 18. The outer ends of the two windings 16 and 17 are connected in circuit relation with a gaseous tube 19. 55

While we have illustrated a gaseous tube, it is to be understood that our invention is not limited to such showing, as our invention may be utilized to energize electrical load of all kinds 5 having a variable resistance. The primary winding, which may be constructed of two parts 13 and 14 is arranged to be intermittently energized from the direct current supply source, indicated by the positive conductor 38 and the negative 10 conductor 39.

While any suitable means may be employed to intermittently energize the primary windings 13 and 14, we preferably utilize an interrupter of the vibrating tuned type. As illustrated, the vibrating contact 27 is carried by a resilient finger 22 having its lower end stationarily mounted upon a support 31. Mounted upon the upper end of the resilient finger 22, is an armature 26 magnetically actuated to the left, as viewed in the 20 drawing, when the coil 25 is energized. The stationary contact 28 is carried upon a finger 23 having its lower end thereof stationarily mounted upon a support 30. The stationary contact 29 is, similarly, mounted upon a finger 24 having its lower end thereof stationarily mounted in a support 32.

The lamp 33 is of the type in which its "cold" resistance is lower than its "hot" resistance. A lamp having these characteristics is found in the 30 "so called" tungsten lamps. The purpose of this lamp is to allow more current to flow through the coil 25 during the period that the vibrating armature is being brought up to its resonant condition, than that which flows after it reaches its 35 resonant condition. This is because, during this period, it requires more current to actuate the vibrating armature 26 than it does after the vibrating armature 26 reaches its resonant condition. By the time the vibrating armature 26 reaches its resonant condition, the filament of the lamp 33 becomes hot, which is accompanied by an increase in its resistance, with the result that the flow of the current in the coil 25 is accordingly decreased. In this manner, the coil 25 45 is prevented from being over heated, as would be the case if the current flowing through the coil 25 were not decreased by the action of the lamp 33.

In explaining the operation of our invention, let it be assumed that the knife switch 37 has been just closed. Upon the closing of the knife switch, the current flows in the following manner: Beginning with the positive supply conductor 38, the current flows through the upper side 50 of the switch 37, the conductors 47, 48, 49 and 50, the lamp 33, the coil 25, the conductor 51, the primary winding 13 to the mid-point 52, the conductor 53, and through the lower side of the switch 37 to the negative supply conductor 39. Upon the establishment of this circuit, the magnetic flux produced by the current flowing 55 through the current 25 attracts the vibrating armature 26 to the left, as viewed in the drawing, until the vibrating contact 27 engages the stationary contact 28. As is noted, just as soon as the vibrating contact 27 engages the stationary contact 28, the coil 25 is shunted and thus de-energized. This means that, the current now flows in the following manner: Beginning with the positive supply conductor 38, the current 60 flows through the upper side of the switch 37, the conductors 41 and 48, the vibrating contact 27, the stationary conductor 28, the conductors 54 and 51, the primary winding 13 to the mid-point 52, the conductor 53, and through the lower

side of the switch 37 to the negative supply conductor 39. Just as soon, however, as the vibrating contact 27 engages the stationary contact 28, which deenergizes the coil 25, the resiliency of the vibrating finger 22 causes the vibrating armature 26 to swing to the left, as viewed in the drawing, until the vibrating contact 27 engages the stationary contact 29. Just as soon as the vibrating contact 27 engages the stationary contact 29, the flow of the current may be traced 10 as follows: Beginning with the positive supply conductor 38, the current flows through the upper side of the switch 37, the conductors 47 and 48, the vibrating contact 27, the stationary contact 29, the conductor 55, the primary winding 14 to the mid-point 52, the conductor 53 and the lower side of the switch 37 to the negative supply conductor 39. After the vibrating contact 27 engages the stationary contact 29, the vibrating armature 26 is again attracted by the flux produced by the coil 25, because the current, which was previously interrupted, again flows through the coil 25 just as soon as the vibrating contact disengages the stationary contact 28. The attractive force of the coil 25 causes the vibrating 20 contact 27 to swing to the left, as viewed in the drawing, and again engage the stationary contact 28. This operation is repeatedly continued, and within a very short period, the vibrating armature 26, rapidly gains momentum and 30 reaches its resonant condition, after which the vibrating contact 27 vibrates between the two stationary contacts 29 and 28 at a substantially uniform rate, which may be determined by the design of the various cooperatively associated 35 parts. The condenser 35, which is connected across the vibrating contact 27 and the stationary contact 28, serves to minimize the arcing, which would otherwise take place upon the interruption 40 of the circuit. Similarly, the condenser 36, which is connected across the vibrating contact 27 and the stationary contact 29, serves to minimize the arcing which would otherwise take place upon 45 the interruption of the circuit. The condenser 34, which is connected in parallel with the coil 25, tends to give a good smooth current flow through the coil 25.

As just previously noted, the action of the interrupter 10 causes rapid reversals of the current flowing through the primary winding 13 and the primary winding 14. In other words, an alternating flux is set up in the magnetic core 11 of the transformer 9. The action of the alternating flux cutting the secondary windings 16 and 17, produces a relatively high initial secondary voltage to ionize the gas in the gaseous tube 19. However, when the gaseous tube is once ionized, the resistance thereof, immediately decreases to a relatively low value. This tends to cause a relatively large secondary current to flow, but it is noted that, as the secondary current tends to increase, there is established a relatively large secondary flux which opposes the passage of the primary flux. Accordingly, a portion of the primary flux is by-passed through the magnetic shunt 21. This means that the voltage induced in the secondary windings is reduced to a relatively low value, with the result that the current flowing through the secondary circuit is maintained or limited at its operating normal value. Inasmuch, as the function of the magnetic shunt 21 tends to limit the value of the secondary current, it likewise follows that the value of the intermittent current impressed upon the primary windings of the transformer is accordingly limited. 75

ited or stabilized. This prevents the contacts of the interrupter 10 from being overloaded, which overloaded condition, if allowed to occur, would soon damage the contact points of the interrupter. In this connection, it is noted that by utilizing a transformer having a magnetic shunt principle, it is possible to utilize an interrupter of the tuned vibrating type, which would otherwise be impossible to utilize with an ordinary transformer, for the reason that when the gas of the gaseous tube 19 once becomes ionized, the increased amount of intermittent current which would flow to the primary windings would be so great as to damage the contacts. It is also pointed out, that by utilizing the magnetic shunt principle, the periodicity of the vibrating contact may vary through a fairly large range, for the reason that the frequency of the interrupted current can be taken care of in the design of the high leakage reactance transformer.

To minimize further the arcing upon the interruption of the current at the contact points of the interrupter 10, we employ the combination of a condenser 40 and a discharge resistor 41. Upon the interruption of the primary current, there is a tendency for the current flowing through either one of the two primary windings, as the case may be, to continue to flow in the same direction as it was previously flowing prior to the interruption. Therefore, the primary current, during the period that the contacts are opened, is urged to flow through the discharge resistor 41, as well as, at the same time, temporarily charging the condenser 40, which is soon dissipated through the resistor 41. While we have shown the combination of a condenser 40 and a discharge resistor 41, we also find from actual tests, that the resistor may be used by itself, or the condenser 40 may be used by itself.

In Figure 2, we utilize an auto, high leakage reactance transformer 60 instead of the high leakage reactance transformer shown in Figure 1. As illustrated the auto transformer comprises a split primary winding 61, a secondary winding 62 and a magnetic shunt 63. The operation of the electrical system, as shown in Figure 2, is substantially the same as that described with reference to Figure 1, and the action of the magnetic shunt 63 is such that, when once the gas of the gaseous tube 64 is ionized, the value of the intermittent current flowing to the primary winding 61 of the auto transformer, is limited to prevent overloading and damaging of the vibrating contacts.

In Figure 3, we utilize a high leakage reactance transformer 65 of a different type. As shown, this transformer comprises a magnetic core 71, two secondary windings 66 and 67, a split primary winding 68, and two magnetic shunts 69 and 70. The split primary winding 68 is intermittently energized by the interrupter 10, in the same manner as that described with reference to Figure 1.

The inner ends of the two secondary windings 66 and 67 are joined together and connected to a suitable ground 72. Each of the outer ends of the secondary windings is connected, respectively, to the upper end of two gaseous tubes 73 and 74. The lower ends of the two gaseous tubes are joined together and connected to the ground 72 by a conductor 75. With this arrangement, each of the gaseous tubes 73 and 74 are energized independently by its corresponding secondary winding.

Immediately upon the energization of the split primary winding 68, there is established a primary flux which flows around the entire magnetic core

11, with substantially none of the flux flowing through the magnetic shunts 69 and 70. The primary flux induces a relatively high initial voltage in both the secondary windings 66 and 67, which ionizes the gas and thus illuminates the two gaseous tubes 73 and 74. Just as soon as the gas of the tubes is ionized, their electrical resistance immediately becomes relatively low, and thus a relatively large secondary current tends to flow through the secondary windings 66 and 67. Consequently, with a sudden rise in the secondary current, the secondary windings 66 and 67 establish a secondary flux that opposes the passage of the primary flux through the secondary windings. Because of the opposition of the secondary flux, a portion of the primary flux is constrained to flow through the two magnetic shunts 69 and 70. The by-passing of the primary flux reduces the voltage induced in the primary windings 66 and 67 to a value which bears a relation to that portion of the primary flux still interlacing the secondary windings. This reduction in the secondary voltage, in turn, limits the value of the secondary current. The degree to which the secondary current is limited, depends upon the reluctance of the magnetic shunts 69 and 70, and upon the design and proportions of the various other co-acting parts of the transformer. The result and effect of the two magnetic shunts 69 and 70 is such that after the gas of the gaseous tube is ionized, the relatively high initial secondary voltage is immediately, and automatically reduced to its normal operating value. Inasmuch as the action of the shunts 69 and 70 tend to limit the value of the secondary current, it likewise follows that the value of the intermittent current impressed upon the split primary winding is accordingly limited, which protects the contacts from being damaged or overloaded.

By reason of the fact that the gaseous tubes 73 and 74 are respectively energized by the secondary windings 66 and 67, it is possible to keep one of the gaseous tubes operating in its normal manner, even though the other gaseous tube may be grounded, which would cause a short upon its corresponding secondary windings. In this connection, let it be assumed that a ground occurs at the upper end of the gaseous tube 74. This means that the secondary winding 67 is now short circuited, and that the secondary current of the secondary winding 67 immediately tends to rise to a high value, which if not limited to a safe value, will burn out the secondary windings and the contacts of the interrupter 10. Under this short circuited condition, the magnetic shunt 70 by-passes substantially all or a major part of the primary flux emanating from the primary winding 68, with the result that the voltage induced in the secondary winding 67 is relatively low. This limits the current flow of the short circuited secondary winding 67, which, in turn, prevents the interrupted current supplied to the primary windings from becoming excessive and burning the contacts of the interrupter 10.

Inasmuch as the magnetic shunt 70 by-passes substantially all or a major part of the primary flux, the secondary winding 66 continues to operate and illuminate the gaseous tube 73. This means that one of the gaseous tubes is kept in operation, even though the other gaseous tube is grounded; while, at the same time, preventing an excessive load imposed upon the interrupter 10.

In Figure 4, we illustrate an arrangement of a balanced, high leakage reactance transformer. The general construction and operation of the

transformer 79 is somewhat similar to the transformer 65, shown in Figure 3, except that there is a third magnetic shunt 80 disposed between the two parts of the split primary winding. In the operation of this transformer, the action of the two outer magnetic shunts 81 and 82 is substantially the same as that described with reference to the magnetic shunts 69 and 70 of Figure 3, and thus either one of the two gaseous tubes may be kept in operation, even though the other gaseous tube may be inoperative. The action of the third magnetic shunt 80 will now be described. The reluctance of the magnetic shunt 80 is relatively high as compared to the reluctance of the magnetic shunts 81 and 82, and thus, substantially no flux flows through the magnetic shunt 80 so long as the electrical load of each of the secondary windings 83 and 84 is the same. But in the event that the electrical load of the secondary windings 83 and 84 become unbalanced, the magnetic shunt 80 by-passes a certain portion of the flux, as well as either one of the two shunts 81 and 82; depending, however, upon which one of the secondary windings is overloaded. In other words, the magnetic shunt 80, or what may be termed a balancing shunt, is adapted, when the two secondary windings 83 and 84 have substantially the same value of the secondary flux opposing the passage of the primary flux, to by-pass a relatively small amount of the primary flux, and is adapted, when the two secondary windings have an unequal value of secondary flux opposing the passage of the primary flux to by-pass a larger amount of the primary flux. This, in turn, protects the contact points of the interrupter from being overloaded or damaged.

From the foregoing description, it is noted that we have so combined a high leakage reactance transformer with an interrupter in such a manner that the value of the intermittent current impressed upon the primary winding of the transformer is limited to a safe value, which prevents the overloading of the contacts, when the resistance of the electrical load decreases.

Although we have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

We claim as our invention:

55 1. A system for converting direct current into alternating current and for utilizing said alternating current to energize an electrical load having a variable resistance comprising, in combination, a magnetic core, a secondary winding disposed to surround a portion of the magnetic core, said portion being designated as a secondary core portion, a primary winding associated with the secondary winding and disposed to surround another portion of the magnetic core, intermittent means for repeatedly interrupting the flow of the direct current and causing same to flow intermittently in the primary winding, and magnetic shunt means having a relatively high reluctance disposed between the primary winding and the secondary winding, said magnetic shunt means being adapted, when the secondary core portion has a relatively low secondary flux opposing the passage of the primary flux, to by-pass a relatively small amount of the primary flux, thereby causing the induction of a relative-

ly high voltage in the secondary winding, and being adapted, when the secondary core portion has a relatively high secondary flux, opposing the passage of the primary flux, to by-pass a relatively large amount of the primary flux, thereby reducing the voltage induced in the secondary winding, with the result that the reluctance of the secondary core portion varies substantially inversely with changes in the resistance of the electrical load to protect the intermittent means 10 from being overloaded by limiting the value of the intermittent current flowing to the primary winding.

2. A system for converting direct current into alternating current and for utilizing the said alternating current to energize an electrical load having a variable resistance comprising, in combination, a magnetic core, a secondary winding disposed to surround a portion of the magnetic core, said portion being designated as a secondary core portion, a primary winding associated with the secondary winding and disposed to surround another portion of the magnetic core, a tuned vibrating interrupter for repeatedly interrupting the flow of the direct current and causing same to flow intermittently in the primary winding, and magnetic shunt means having a relatively high reluctance disposed between the primary winding and the secondary winding, said magnetic shunt means being adapted, when the secondary core portion has a relatively low secondary flux opposing the passage of the primary flux, to by-pass a relatively small amount of the primary flux, thereby causing the induction of a relatively high voltage in the secondary winding, and being adapted, when the secondary core portion has a relatively high secondary flux opposing the passage of the primary flux, to by-pass a relatively large amount of the primary flux, thereby reducing the voltage induced in the secondary winding, with the result that the reluctance of the secondary core portion varies substantially inversely with changes in the resistance of the electrical load to protect the intermittent means 15 from being overloaded by limiting the value of the intermittent current flowing to the primary winding.

3. A system for converting direct current into alternating current and for utilizing the said alternating current to energize a plurality of electrical loads having a variable resistance comprising, in combination, a magnetic core, a secondary winding disposed to surround a portion of the magnetic core, said portion being designated as a secondary core portion, a second secondary winding associated in spaced relation with the first-mentioned secondary winding and disposed to surround another portion of the magnetic core, said portion being designated as the second secondary core portion, a primary winding associated with the secondary windings and disposed to surround another portion of the magnetic core, intermittent means for repeatedly interrupting the flow of the direct current and causing same to flow intermittently in the primary winding, means for grounding one end of each of the secondary windings, means for connecting an electrical load between the grounding means and each of the other ends of the secondary windings, thus energizing one of the electrical loads by the first-mentioned secondary winding and the other electrical load by the second-mentioned secondary winding, and two magnetic shunt means each having a relatively high reluctance and each being disposed between the primary winding and

each of the secondary windings, the arrangement of the magnetic core and the magnetic shunt means being adapted such that, when the value of the secondary flux of each of the two secondary core portions opposing the passage of the primary flux is unequal resulting from an unequal load distribution upon the two secondary windings or from a short circuited condition of the like imposed upon one of the secondary windings, the magnetic shunt, which is disposed between the primary winding and the secondary winding surrounding the secondary core portion having the high secondary flux opposing the passage of the primary flux, by-passes a larger amount of the primary flux than does the other shunt means, thereby causing less primary flux to interlace the secondary winding surrounding the secondary core portion having the higher secondary flux opposing the passage of the primary flux, and to induce a lower voltage therein which protects the intermittent means from being overloaded by limiting the current flowing through the said secondary winding having the lower resistance load or short circuited condition, and causing the primary flux to interlace the secondary winding surrounding the secondary core portion having the lower secondary flux opposing the passage of the primary flux and to induce a voltage therein to keep the said secondary winding in operation for energizing its electrical load.

4. A system for converting direct current into alternating current and for utilizing the said alternating current to energize an electrical load having a variable resistance comprising, in combination, a magnetic core, a two part primary winding disposed to surround a portion of the core, a secondary winding associated in spaced relation with the primary winding and disposed to surround another portion of the core, said portion being designated as the secondary core portion, intermittent means for repeatedly interrupting the flow of the direct current and causing same to flow intermittently in the primary winding, a magnetic shunt disposed between the primary winding and the secondary winding, said magnetic shunt being adapted, when the secondary core portion has a relatively low secondary flux opposing the passage of the primary flux produced by the primary winding to by-pass a relative small amount of the flux produced by the primary winding, thereby causing the induction of a relatively high voltage in the secondary winding, and said magnetic shunt being adapted when the secondary core portion has a relatively high secondary flux opposing the passage of the primary flux produced by the primary winding to by-pass a larger amount of the flux produced by the primary winding, thereby reducing the voltage induced in the secondary winding with the result that the reluctance of the secondary core portion varies substantially inversely with changes in the resistance of the electrical load to protect the intermittent means from being over loaded, a second secondary winding associated in spaced relation with the primary winding and disposed to surround another portion of the core, said portion being designated as the second-mentioned secondary core portion, a second magnetic shunt disposed between the primary winding and the second-mentioned secondary winding, said second-mentioned magnetic shunt being adapted, when the second-mentioned secondary core portion has a relatively low secondary flux opposing the passage of the primary flux produced by the primary winding.

primary winding to by-pass a relative small amount of the flux produced by the primary winding, thereby causing the induction of a relatively high voltage in the second-mentioned secondary winding, and said second-mentioned magnetic shunt being adapted, when the second-mentioned secondary core portion has a relatively high secondary flux opposing the passage of the primary flux produced by the primary winding, to by-pass a larger amount of the flux produced by the primary winding, thereby reducing the voltage induced in the second-mentioned secondary winding with the result that the reluctance of the second-mentioned secondary core portion varies substantially inversely with changes in the resistance of the electrical load, to protect the intermittent means from being over loaded, and a balancing magnetic shunt disposed between the two parts of the primary windings, said balancing shunt being adapted, when the two secondary core portions have substantially the same value of secondary flux produced by the primary winding to by-pass a relative small amount of the flux produced by the primary winding, and said balancing shunt being adapted, when the two secondary core portions have an unequal value of secondary flux opposing the passage of the flux produced by the primary winding to by-pass a larger amount of the flux produced by the primary winding, thereby causing a relatively small amount of the said primary flux to interlace the secondary winding surrounding the secondary core portion having the higher value of opposing secondary flux and to induce a relatively low voltage therein, to protect the intermittent means from being overloaded, and causing a relatively large amount of the said primary flux to interlace the said secondary winding surrounding the secondary core portion having the lower value of opposing secondary flux, and to induce a relatively high voltage in the said secondary winding and thus keeping the said secondary winding in operation for energizing its electrical load.

5. A system for converting direct current into alternating current and for utilizing the said alternating current to energize an electrical load having a variable resistance comprising, in combination, a magnetic core, a two part primary winding disposed to surround a portion of the core, a secondary winding associated in spaced relation with the primary winding and disposed to surround another portion of the core, said portion being designated as the secondary core portion, intermittent means for repeatedly interrupting the flow of the direct current and causing same to flow intermittently in the primary winding, a magnetic shunt disposed between the primary winding and the secondary winding, said magnetic shunt being adapted, when the secondary core portion has a relatively low secondary flux opposing the passage of the primary flux produced by the primary winding, to by-pass a relative small amount of the flux produced by the primary winding, thereby causing the induction of a relatively high voltage in the secondary winding, and said magnetic shunt being adapted when the secondary core portion has a relatively high secondary flux opposing the passage of the primary flux produced by the primary winding, thereby reducing the voltage induced in the secondary winding with the result that the reluctance of the secondary core portion varies substantially inversely with changes in the resistance of the electrical load to protect the intermittent means from being over loaded, a second secondary winding associated in spaced relation with the primary winding and disposed to surround another portion of the core, said portion being designated as the second-mentioned secondary core portion, a second magnetic shunt disposed between the primary winding and the second-mentioned secondary winding, said second-mentioned magnetic shunt being adapted, when the second-mentioned secondary core portion has a relatively low secondary flux opposing the passage of the primary flux produced by the primary winding, to by-pass a larger amount of the flux produced by the primary winding, thereby reducing the voltage induced in the secondary winding with the result that the reluctance of the secondary core portion varies substantially inversely with changes in the resistance of the electrical load,

to protect the intermittent means from being over loaded, a second secondary winding associated in spaced relation with the primary winding and disposed to surround another portion of the core, said portion being designated as the second-mentioned secondary core portion, a second magnetic shunt disposed between the second mentioned primary winding, and the second-mentioned secondary winding, said second-mentioned magnetic shunt being adapted, when the second-mentioned secondary core portion has a relatively high secondary flux opposing the passage of the primary flux produced by the primary winding to by-pass a relatively small amount of the flux produced by the primary winding, thereby causing the induction of a relatively high voltage in the second-mentioned secondary winding, and said second-mentioned magnetic shunt being adapted, when the second-mentioned secondary core portion has a relatively high secondary flux opposing the passage of the primary flux produced by the second-mentioned primary winding to by-pass a larger amount of the flux produced by the primary winding, thereby reducing the voltage induced in the second-mentioned secondary winding with the result that the reluctance of the second-mentioned secondary core portion varies substantially inversely with changes in the resistance of the electrical load to prevent the intermittent means from being overloaded.

6. A system for converting direct current into alternating current and for utilizing the said alternating current to energize an electrical load having a variable resistance comprising, in combination, a transformer having a primary winding and a secondary winding, intermittent means for repeatedly interrupting the flow of the direct current and causing same to flow intermittently in the primary winding, and magnetic flux means to protect the intermittent means from being overloaded by limiting the value of the intermittent current flowing to the primary winding when the resistance of the electrical load decreases.

7. A system for converting direct current into alternating current and for utilizing the said alternating current to energize an electrical load having a variable resistance comprising, in combination, a high leakage reactance transformer having a primary winding and a secondary winding, and intermittent means for repeatedly interrupting the flow of the direct current and causing same to flow intermittently to the primary winding, the combination of the intermittent means and the high leakage reactance transformer being such that the intermittent means is protected from being overloaded by the action of the transformer limiting the value of the intermittent current flowing to the primary winding when the resistance of the electrical load decreases.

8. A system for converting direct current into alternating current and for utilizing the said al-

ternating current to energize an electrical load having a variable resistance comprising, in combination, an auto transformer having two winding portions, intermittent means for repeatedly interrupting the flow of the direct current and causing same to flow intermittently in one of the winding portions, and magnetic flux means to protect the intermittent means from being overloaded by limiting the value of the intermittent current flowing to the said winding portion when the resistance of the electrical load decreases.

9. A system for transforming electrical energy to energize an electrical load having a variable resistance comprising, in combination, a transformer having a primary winding and a secondary winding, a tuned vibrating interrupter for causing current to flow intermittently in the primary winding, magnetic shunt means disposed between the primary and the secondary windings to protect the said tuned vibrating interrupter from being overloaded by limiting the value of the intermittent current flowing to the primary winding when the resistance of the electrical load decreases, a coil for magnetically operating the tuned vibrating interrupter, means for energizing the coil, and automatic means connected in series with the coil for decreasing the energization of the coil after the tuned vibrating interrupter is set in operation.

10. A system for transforming electrical energy to energize an electrical load having a variable resistance comprising, in combination, an auto transformer having two winding portions, a tuned vibrating interrupter for causing current to flow intermittently in one of the winding portions, magnetic shunt means disposed between the primary and secondary windings to protect the said tuned vibrating interrupter from being overloaded by limiting the value of the intermittent current flowing to the said winding portion when the resistance of the electrical load decreases, a coil for magnetically operating the tuned vibrating interrupter, means for energizing the coil, and automatic means connected in series with the coil for decreasing the energization of the coil after the tuned vibrating interrupter is set in operation.

11. A system for converting direct current into alternating current and for utilizing the said alternating current to energize an electrical load having a variable resistance comprising, in combination, a transformer having a primary winding and a secondary winding, intermittent means for repeatedly interrupting the flow of the direct current and causing same to flow intermittently in the primary winding, and magnetic shunt means disposed between the primary winding and the secondary to protect the intermittent means from being overloaded by limiting the value of the intermittent current flowing to the primary winding when the resistance of the electrical load decreases.
